UNITED STATES PATENT OFFICE.

GEORGE W. DUNHAM, OF DETROIT, MICHIGAN, ASSIGNOR TO CHALMERS MOTOR COMPANY, OF DETROIT, MICHIGAN, A CORPORATION OF MICHIGAN.

DESIGN FOR AN AUTOMOBILE-BODY.

42,732.

Specification for Design.

Patented July 9, 1912.

Application filed September 18, 1911. Serial No. 650,059. Term of patent 14 years.

To all whom it may concern:

Be it known that I, GEORGE W. DUNHAM, a citizen of the United States of America, residing at Detroit, in the county of Wayne and State of Michigan, have invented a certain new, original, and ornamental Design for Automobile-Bodies, of which the following is a specification, reference being had therein to the accompanying drawings, forming part thereof, in which—

Figure 1 is a perspective view of an automobile body, showing my new design; and Fig. 2 is a similar view, taken from the side.

I claim:

The ornamental design for an automobile body, as shown.

GEORGE W. DUNHAM.

Witnesses:

C. E. GREGORY,
RAY J. MANER.
